KNITTING MACHINE

Harry Agulnek, Brooklyn, N. Y., assignor to
 Samuel Mishcon, doing business as Supreme
 Knitting Machine Co., Brooklyn, N. Y.

Application March 19, 1935, Serial No. 11,769

6 Claims. (Cl. 66—50)

This invention relates to a cam for circular knitting machines, and particularly to that type of cam positioned intermediate the pattern wheel and stitch cam serving the auxiliary purpose of drawing down an unraised needle leaving the pattern wheel to a position where it will be out of engagement with the yarn.

As is the common practice in circular knitting machines, there are employed a plurality of pattern wheels or other selective elevating devices each of which is adapted to raise a selected coating needle to a predetermined level where it remains until it strikes the downwardly sloping stitch cam; and where there is no elevating member, such as the inserts used in a pattern wheel, the needle will remain in its idle unraised position until it similarly strikes the stitch cam at a lower point therealong, to be directed downwardly. In both of these cases, the needle operatively engages the yarn in a manner well known to the art. Where it is desired, however, to keep the needle out of engagement with the yarn to produce certain kinds of fabrics, an auxiliary cam is interposed between the wheel and stitch cam, for the purpose of drawing down the needle before the receiving point of the yarn is reached. Cams of this class are generally, according to common practice, an integral part of the block or section which carries the pattern wheel and stitch cam, so that should it be necessary to effect any repairs or changes on the said auxiliary cam, it is always necessary to detach the entire section, with all the mountings thereon, for this purpose. To overcome these disadvantages I have hence conceived this invention, whereby the auxiliary cam is independent from the section or block, and is separately attached preferably to the cam ring upon which the section itself is mounted. This arrangement not only enables the said auxiliary cam to be independently detached for repairs, but is of such a nature as to be adaptable for use on a knitting machine regardless of the size of the feed sections employed thereon.

It is still another object of my invention to provide means wholly within or a part of the auxiliary cam mounting for rendering said cam entirely inoperative by manual manipulation.

And it is a further object of this invention to provide means for directing a needle to a predetermined level other than the usual idle and elevated levels characteristic of customary knitting machine practice, so as to produce special types of fabrics.

Other objects, features and advantages will

appear from the drawing and the description hereinafter given.

Referring to the drawing,

Figure 1 is a vertical sectional view of a portion of a circular knitting machine, showing the cam constituting my invention in operative position with respect to a needle, a cam ring, and the pattern wheel shown by dot-dash lines. 5

Figure 2 is a fragmentary plan view showing the auxiliary cam constituting my invention secured to the cam ring. 10

Figure 3 is a plan view of a section of a circular knitting machine, showing the auxiliary cam in position, and the section carrying the pattern wheel mounting in place. 15

Figure 4 is an elevation, looking from the cylinder, showing the arrangement of lifting cam, pattern wheel, the auxiliary cam constituting my invention and the stitch cam. 20

Figure 5 shows the spring actuated cam element with a needle traveling towards the cam surface. 20

Figure 6 shows the cam element of Figure 5 in a retracted position when a needle butt engages the upper portion thereof. 25

Figure 7 is a perspective view of the unit containing my invention, and 25

Figure 8 is a vertical fragmentary section of a modification of the cam element and mounting therefore, showing the means employed for manually retracting the cam element into an inoperative position. 30

Referring to the drawing, the auxiliary cam unit 10 containing my invention is mounted upon the cam ring 11 and secured thereto by the countersunk screws 12—the cam element 13 being positioned intermediate the pattern wheel 14 and the stitch cam 15. The pattern wheel is mounted upon the section 16 which is secured to the cam ring 11 by the screws 17 and 18, the bifurcated support 19 serving as the direct mounting for the wheel. 35

In the preferred form of my invention, the cam element 13 is a part of the unitary member 10 which contains thereon the lifting cam surface 20—the said cam element being joined to and preferably integral with the arm 21 positioned within the channel 22, said arm being mounted upon the pin 23 extending transversely through the channel and urged towards and against the wall 10a (the base of the channel) by the spring 24 to hold the cam element 13 in its projected operative position. The said cam element 13 has a horizontal portion 25 containing a tapered surface 55

26 adjacent the pattern wheel, and also contains a downwardly inclined surface spaced from the wall 10 and thereby forming a passageway 27 to accommodate downwardly moving butts of needles 5 engaged thereby.

Where it is desired to employ means to render the cam inoperative by retracting it, the arm 21a (see Figure 8) of the cam element contains the internally threaded boss 28 which carries and through which extends the screw 29 in constant abutment with the wall 10a,—a spring similar to that identified by the numeral 24 constantly urging the arm and screw towards said wall.

In the operation of this device, each needle 15 such as that identified by the numeral 30, is carried along with the rotating cam ring until the butt thereof strikes the lifting cam surface 20, which raises it to the idling position, bringing it up to a level where it can enter the slots in the pattern wheel 14. Where there are jacks or inserts in said wheel, the butts 31 will be lifted thereby and the needle carried along with the cylinder, the path of the butts of the elevated needles being indicated by the dot-dash lines 32, said butts 25 striking the surface 33 of the stitch cam 15 which draws them downwardly to enable the needles to perform a stitching operation. Where, however, there is no insert in the wheel, the butt of a needle, such as 34, will pass therethrough without being elevated and will be carried along the level 35 until it strikes the auxiliary cam element 13, which directs it downwardly to a level 30 where it is out of engagement with the yarn.

Should the butt of a needle for some reason 35 move along the level of the horizontal portion 25, it will strike the tapered or angulated surface 26 to cause a retraction of the cam element 13 against the action of the spring 24,—thereby removing the said cam element as an obstruction to the continued movement of the needle.

In the event it is desired to render the cam device inoperative, so as to permit the butts of the unelevated needles to move along without striking the auxiliary cam but to continue until they 45 strike the surface 33 of the stitch cam, the screw 29 (Figure 8) is manipulated to move the arm 21a forwardly away from the cylinder, thereby shifting it out of the path of the needle butts as indicated by the dot-dash lines. It is thus apparent that by a simple manipulation of the screw 29, the cam element can be either brought into its projected operative position, or retracted into an inoperative position.

Inasmuch as the cam member 10 is attached 55 directly to the cam ring 11, and not to the section 16, it is obvious that this member can readily be detached from the machine without affecting the said section 16 and the stitch cam and pattern wheel mounted thereon. With this construction, 60 the auxiliary cam is absolutely independent of the section 16 and the superimposed parts, and can be removed from the machine and repaired as a separate and independent unitary element. As the entire auxiliary cam mechanism is contained within the cam member 10, any and all repairs and adjustments of any parts thereof can readily be made after it is detached from the cam ring. Furthermore, the very same cam member 10 can be used on a knitting machine regardless of 65 the size of the feed section 16, which constitutes a decided advantage over other forms of auxiliary cams which are either an integral or component part of the section.

In the preferred form shown on the drawing, 70 the auxiliary cam constituting my invention is

combinatively used as a part of the lifting cam, which makes the unit very compact, economical of space and easy to handle.

It is of course understood that the various embodiments above described and shown in the drawing are illustrative of my invention and not employed by way of limitation, inasmuch as numerous changes and modifications may be made within the scope of the appended claims without departing from the spirit of this invention. 10

What I claim is:

1. In a knitting machine having thereon a cam ring, needle elevating means, a stitch cam for lowering needles selectively raised by said elevating means, a unitary member attached to said cam ring and containing a lifting cam surface and having operably attached thereto a pivotally mounted auxiliary cam operatively positioned before said stitch cam and after said elevating means for lowering needles raised by said lifting cam surface and unelevated by said elevating means. 15

2. In a knitting machine having thereon a cam ring, needle elevating means, a stitch cam for lowering needles selectively raised by said elevating means, and a unitary member attached to said cam ring; said member containing a lifting cam surface, a pivotally mounted auxiliary cam operatively positioned before said stitch cam and after said elevating means for lowering needles raised by said lifting cam surface and unelevated by said elevating means, fixed limiting means to hold the auxiliary cam against movement beyond its operative position, and spring means mounted on and entirely contained within said unitary 35 member and constantly urging said auxiliary cam towards said limiting means and yieldably holding it against retraction. 25

3. In a knitting machine having thereon a cam ring, needle elevating means, a stitch cam for lowering needles selectively raised by said elevating means, a unitary member attached to said cam ring and containing a lifting cam surface, a recessed portion, a retractable auxiliary cam operatively positioned before said stitch cam and after said elevating means for lowering needles raised by said lifting cam surface and unelevated by said elevating means, said auxiliary cam containing an operative surface joined to an arm extending within and pivotally attached to said 45 recessed portion, fixed limiting means to hold the auxiliary cam against movement beyond its operative position, and spring means within said recessed portion and in engagement with said arm for urging said auxiliary cam towards said limiting means and yieldably holding it against retraction. 50

4. In a circular knitting machine having thereon a cam ring, needle elevating means, a stitch cam for lowering needles selectively raised by said elevating means, and a unitary member attached to said cam ring and containing a lifting cam surface, a channel having its base adjacent and in facing relation to the cylinder of the machine, a retractable auxiliary cam operatively positioned before said stitch cam and after said elevating means for lowering needles raised by said lifting cam surface and unelevated by said elevating means, said auxiliary cam containing an operative surface joined to an arm extending into said channel and pivotally mounted on a pin supported by the lateral walls of the channel and extending transversely thereacross, and spring means mounted on said pin and in engagement with said arm for yieldably holding it in its pro- 70 75 80 85 90 95

jected position against the base of the channel. 5. In a circular knitting machine having there-
on a cam ring, needle elevating means, a stitch
cam for lowering needles selectively raised by
said elevating means, and a unitary member
5 attached to said cam ring and containing a lift-
ing cam surface, a wall adjacent and in facing
relation to the cylinder, a pivotally mounted
auxiliary cam operatively positioned before said
10 stitch cam and after said elevating means for
lowering needles raised by said lifting cam sur-
face and unelevated by said elevating means,
said auxiliary cam comprising an operative sur-
face and an arm joined thereto, said operative
15 surface being in spaced relation to the adjacent
edge of said wall, and spring means entirely con-
tained within said member and yieldably urging

said arm towards the cylinder and against said
wall which serves as a limiting stop to hold the
auxiliary cam in its operative position.

6. In a circular knitting machine, a cam ring
an independent unitary member attached direct-
ly to the cam ring and containing a wall adjacent
and in facing relation to the cylinder, a pivotally
mounted auxiliary cam comprising an operative
surface and an arm joined thereto, said operative
surface being in spaced relation to the adjacent 10
edge of said wall, and said arm containing an
internally threaded boss; an adjusting screw car-
ried by and in threaded engagement with said
boss and having its end in abutment with said
wall, and spring means yieldably urging said arm 15
towards said wall.

HARRY AGULNEK.
